UNITED STATES PATENT OFFICE.

WALTER L. BOARDMAN, OF DECATUR, ILLINOIS.

SPARK-PLUG CLEANER.

1,347,573.

Specification of Letters Patent. Patented July 27, 1920.

Application filed August 11, 1919. Serial No. 316,661.

To all whom it may concern:

Be it known that I, WALTER L. BOARDMAN, a citizen of the United States, a resident of Decatur, in the county of Macon 5 and State of Illinois, have invented new and useful Improvements in Spark-Plug Cleaners, of which the following is a specification.

This invention relates to certain new and 10 useful improvements in a spark plug cleaner, and especially to a cleaning tool adapted more particularly for the cleansing of the A-C type of plug which necessitates the use of four tools, namely, a screw 15 driver, scraper, file, and gage.

The principal object of the invention is to provide an improved single tool capable of performing these combined functions in an efficient and facile manner.

20 A further object resides in the provision of a light combination and integral tool having an intermediate handle or grip portion, a scraping blade on one terminal, and a file on the other of a predetermined thickness to constitute a gage for facilitating the 25 proper setting of the sparking points or terminals of the plug.

Further, the invention resides in the features of construction hereinafter described 30 and claimed, reference being had to the accompanying drawing, wherein,

Figure 1 is a perspective view of the combination spark-plug cleaning tool;

Fig. 2 is a similar view of the tool depicting the opposite or file side thereof;

Fig. 3 is a transverse section on line 3—3 of Fig. 1, through the file and gage part of the tool; and

Fig. 4 is a side elevation of the tool, illustrating it functioning as a gage.

The tool comprises a steel bar reduced at one end to provide a tapering blade 1 having one side face 2 convexed substantially to the inside curvature of the spark plug 45 and both longitudinal edges sharpened for scraping the carbon deposit from the inner wall of the plug.

The opposite end of the bar or body is flattened to a thickness equal to the space 50 between two properly set points of the plug whereby to serve as a gage 3 for setting the points subsequent to cleaning the same, as indicated in the two instances shown at 4

and 5. In the instance at 4, the end 7 is shown as being used as a gage, or also used 55 in separating the points preparatory to filing the end of the right-angled terminal, the latter filing being depicted in the instance as shown at 5. The instance 5 also shows the blade used as a gage to determine proper 60 spacing of the parts. After filing, the points are moved together and then the blade is inserted between the same as depicted in full and dotted lines in Fig. 4 to determine proper spacing. One side face 65 of the gage, preferably the face opposite to the convex face of the scraping blade 1, is formed into a file 6 by which the plug points may be abraded and more easily 70 cleaned.

The extreme end of the file and gage part terminates in a screw-driver 7, especially 75 useful in cleaning plugs of the well known A-C type. The handle 8 is formed between the scraper and gage parts by reducing the bar of steel from one side only whereby the handle will project therefrom and leave the opposite side, which is provided with the filing surface, flat. The single hand thus serves while functioning with 80 either end of the tool. It will be noticed that during the process of filing the points, the gage may simultaneously be brought into play so that the points may be pressed together or otherwise set in properly spaced 85 relation. The single tool embodies all the tool parts essential for cleaning a plug, each part acting to facilitate the operation of another part so that a plug may be expeditiously cleaned in an efficient manner. 90

What I claim is:

1. A combined spark-plug point cleaner and gage composed of a member having a blade formed with a smooth face on one side and having the face of its opposite side 95 provided with file teeth so that the smooth face can engage and slide on the straight point of the spark plug while the file teeth are acting upon or cutting the end of the usual right-angled point of the spark plug, 100 and said blade being of such thickness as to act as a gage to determine proper spacing of the points, the free end of the blade being smooth on both faces so as to allow it to be used to wedge the points apart in initially 105 introducing the blade between the points.

2. A spark-plug cleaning tool comprising a blade having a predetermined thickness equal to the proper spacing of the points of the plug, whereby the same may function as
5 a gage to set the points during the filing thereof, said blade having file teeth on one face and its opposite face smooth so that it

may engage and slide on the straight point of the spark plug while the file teeth are acting upon or cutting the end of the usual 10 right-angled point of the spark plug.

In witness whereof, I have hereunto affixed my hand this 31st day of July, 1919.

WALTER L. BOARDMAN.
